F. J. RUFF AND W. R. EKINS.

SHOE PRESSER.
APPLICATION FILED JUNE 2, 1919.

1,334,968.

Patented Mar. 30, 1920.

UNITED STATES PATENT OFFICE.

FRANK J. RUFF AND WALTER R. EKINS, OF ST. LOUIS, MISSOURI, ASSIGNEES OF ONE-
THIRD TO GUSTAVE A. COOK, OF ST. LOUIS, MISSOURI.

SHOE-PRESSER.

1,334,968.

Specification of Letters Patent. Patented Mar. 30, 1920.

Application filed June 2, 1919. Serial No. 301,163.

To all whom it may concern:

Be it known that we, FRANK J. RUFF and WALTER R. EKINS, citizens of the United States, residing at St. Louis, State of Missouri, have invented certain new and useful Improvements in Shoe-Pressers, of which the following is a full, clear, and exact description, reference being had to the accompanying drawings, forming a part hereof.

10 The present invention is directed to improvements in shoe pressers and particularly to pressers for removing the wrinkles from the quarter lining of shoe uppers. The object of the invention is to provide a presser 15 by which the wrinkles may be effectively removed in a single operation by pressure alone in conjunction with heat applied directly to the shoe. A further object is to provide a machine which is simple, easily 20 and quickly manipulated, cheap to construct, and one possessing further and other advantages better apparent from the following detailed description in connection with the accompanying drawings, in which—

25 Figure 1 represents a side elevation of the machine showing a shoe applied thereto; Fig. 2 is a vertical transverse section on the line 2—2 of Fig. 1; Fig. 3 is a top plan of the shoe support or saddle with walls 30 partly broken away; Fig. 4 is a side elevation of the saddle with walls partly broken away; and Fig. 5 is an edge view of the guide-yoke for the pedal lever, shown broken at the middle, the lever being in 35 cross-section and broken away.

Referring to the drawings, 1 represents a suitable shoe support or saddle contoured conformably to the counter and quarter of a shoe upper, the same being provided with 40 an extension or plate 2 by which it may be secured or bolted to a suitable bench or table 3, the inner end of the saddle bearing against the edge of the table (Fig. 1). The counter and quarter of the shoe S 45 when the latter is passed over the saddle are supported along the upper concaved seat d thereof, the contour of the seat conforming to said counter and quarter as clearly shown in the drawings. The saddle

50 is provided with a longitudinal passage-way h adjacent the seat d for the insertion of a tube 4 carrying an insulated heating coil 5, which is in circuit with the conducting wires w well understood in the art, said 55 wires leading to any available source of electrical energy (not shown). The saddle

thus becomes electrically heated; but it is to be understood that we are not to be limited to an electrically heated saddle as the same may be heated by other means, such as solid or gaseous fuel, steam or hot gases, the electric heating being a matter of convenience and resulting in a simpler construction of saddle.

Hinged to a suitable forked casting 6 bolted to the floor F, beneath the bench 3, is one end of a pedal lever 7, the same being provided near its free end with a lug 8 to which is attached one end of an expansion spring 9 the opposite end whereof is hooked to a loop 10 hinged to a fitting 11 at the adjacent ends of suitable straps or bands 12, the opposite ends of the straps being connected to a preferably leather pad 13 shaped to conform to and snugly embrace the shoe quarter deposited on the seat d of the saddle 1. The members 12, 12, and 13 jointly form an endless band or belt which may be conveniently swung over the shoe deposited on the saddle as clearly obvious from the drawings. The saddle is provided in the rear with a ridge or nose 14 just beyond the seat d, said nose being raised sufficiently above the supporting surface of the seat to permit the pad 13 to be raised and temporarily supported by the nose when the occasion arises to remove the shoe from the saddle (see dotted position Fig. 1). The lever 7 is guided between the sides of a suitable yoke 15 bolted to the floor, one arm 75 or leg of the yoke terminating a suitable distance above the floor. The opposite leg is provided on the inner face near the bottom thereof with a locking stud or pin 16 under which the adjacent edge of the lever 7 may 80 be temporarily brought so as to hold the pad 13 tightly to the shoe, it being understood that the lever is hinged loosely to the casting 6 and susceptible of sufficient lateral movement to permit the lever to swing vertically between the yoke legs or arms out of the path of the stud 16, or be brought under the stud (Figs. 1, 5,) when it becomes necessary to hold down the lever to cause the pad 13 to hug the shoe.

The operation is substantially as follows: When the shoe lining of the quarter is to be pressed, the shoe S is passed over the heated saddle 1, and deposited on the seat d. The operator then passes the pad 13 over the shoe so as to envelop the quarter and then with his foot depresses the pedal lever 7 to

the lower dotted position shown in Fig. 1, bringing the lever under the pin or stud 16 (Figs. 1, 5,) and thereby locking the lever against upward movement. In its depressed 5 position the lever exerts a draft on the spring 9 and a corresponding pull on the straps 12 and pad 13, thereby causing the pad to snugly grip the shoe and press the same firmly against the seat of the saddle. 10 The locking of the pedal lever in its depressed position permits the pressing operation to be maintained and continued until the pedal is released, the locking of the lever of one machine permitting the operator 15 to attend to the levers of a series of machines in succession. By the time the lever of the last machine is depressed and locked, that of the first machine may be released and the shoe removed so that no time need 20 be lost by the operator in attending to the machines. By having on hand a sufficient number of machines, the pressed shoes may be removed in succession, the pressing of the first shoe being finished by the time a shoe 25 is applied to the last machine of the series. To remove a shoe, the operator first releases the pedal lever 7 from the stud 16, then lifts the pad 13 and deposits it on the nose 14 of the saddle, the draft thus exerted on 30 the straps 12 lifting the pedal lever 7 to the upper dotted position shown in Fig. 1. The deposit of the pad on the nose 14 releases the shoe from the pad thereby permitting the shoe to be pulled sidewise off the 35 saddle. The shoe being removed, another is slipped over the saddle and the pad pushed back over the shoe, the operator thereupon depressing and locking the pedal lever 7 and causing the pad 13 to hug and 40 snugly embrace the shoe and press the wrinkles therefrom. The usual time consumed in the pressing of a shoe is a minute, more or less, so that at least half a dozen machines may be operated by a single attendant, it requiring about that length of 45 time to mount as many shoes.

Obviously, the machine is susceptible of many changes as to details, such changes not necessarily involving a departure from the nature or spirit of the invention. The 50 presser is not necessarily restricted in its application to foot-wear, but may be used for pressing other stock, as must be obvious to those skilled in the art. The spring 9 obviously operates as a cushioning member, and likewise regulates the tension on the 55 straps 12 and hence the pressure that the pad 13 exerts on the quarter of the shoe. It likewise serves to automatically restore the lever 7 to its normal raised position when the lever is released from under the pin or stud 16. The pad 13 may of course be any suitable sheet or cover of pliable material adapted to be passed snugly over 60 the shoe so as to grip the same and press it 65

to the saddle. So too, the members 12 and 13 may be of the same material and be of one piece if desired.

Having described our invention what we claim is:

1. In a presser for shoes and the like, a shoe support having its surface contoured to the shape of the quarter of the shoe to be supported, means for heating the support, a pad embracing the quarter of the shoe deposited on the support, and means for imposing tension on the pad to draw the same tightly about the shoe and press the quarter to the heated surface of the support. 70

2. In a presser for shoes and the like, a shoe support contoured to the shape of the quarter and counter of the shoe to be supported, means for heating said support, a pad for embracing the shoe quarter deposited on the support, and means for drawing the pad tightly about the shoe to press the quarter to the heated surface of the support. 80

3. In a shoe presser, a heated shoe support or saddle contoured to the shape of the counter and quarter of the shoe to be supported, a pad or cover for embracing the shoe quarter deposited on the support, a pedal lever, a yielding spring and intermediate connections between the lever and 90 pad, the parts operating substantially as and for the purpose set forth.

4. A shoe presser comprising an electrically heated fixed saddle having a seat contoured to the counter and quarter of the shoe to be pressed, a pedal lever hinged at one end beneath the saddle, a pad or sheet adapted to be passed around the shoe quarter, a spring having one end secured to the lever at a suitable point removed from the 100 fulcrum thereof, intermediate connections between the opposite end of the spring and the ends of the pad, means for guiding the lever, and means for locking the same in position while maintaining a draft on the 105 pad. 110

5. In a shoe presser, a saddle for the shoe contoured to the shape of the shoe counter and quarter, and a nose or ridge formation on the saddle raised above the shoe-supporting surface of the saddle. 115

6. In a shoe presser, a saddle for the shoe having a depressed surface contoured to the counter and quarter of the shoe, a nose or ridge at one end raised above said depression, and a coöperating pressing sheet or pad adapted to either engage the shoe, or be raised out of contact with the shoe and supported by the nose. 120

In testimony whereof we affix our signatures at St. Louis, State of Missouri, this 31st day of May, 1919. 125
